UNITED STATES PATENT OFFICE.

ROBERT H. JENSON, OF HOUSTON, TEXAS, ASSIGNOR, BY MESNE ASSIGNMENTS, TO BROWN METAL AND CORK COMPANY, A CORPORATION.

SHAPING MACHINE.

Application filed September 19, 1927. Serial No. 220,419.

This invention relates to new and useful improvements in a shaping machine.

One object of the invention is to provide a machine of the character described specially 5 designed for the purpose of shaping units of cork, and the like, into spherical form, and thus adapting them to be used as floats for fishing tackle.

Another object of the invention is to provide 10 a float making machine of the character described which is of simple construction, may be easily operated and which is very efficient in use.

With the above and other objects in view 15 this invention has particular relation to certain novel features of construction, operation and arrangement of parts an example of which is given in this specification and illustrated in the accompanying drawings, 20 wherein:—

Figure 1 shows a side elevation of the machine, partly in section.

Figure 2 shows a sectional view thereof taken on the line 2—2 of Figure 1.

Figure 3 shows an end view of the machine, partly in section.

Figure 4 shows a sectional view of an incomplete float, and

Figure 5 shows a side view of the complete float.

Referring now more particularly to the drawings, wherein like numerals of reference designate similar parts in each of the figures the numerals 1 designate the legs of the 35 framework which are connected by the upper and lower longitudinal angle bars 2, 2 and 3, 3 and the transverse end braces 4, 4.

There is a drive shaft 5, mounted to rotate in suitable bearings on the lower cross bars 40 3, 3 and fixed on one end of this shaft there is a drive pulley 6 to receive a driving belt, not shown. Fixed on the other end of this shaft there is a small belt pulley 7 and the shaft 5 is extended beyond said pulley 7 and forms a support on which the feed lever 8 has a bearing. This feed lever extends approximately vertically and at its upper end there is another belt pulley 9, aligned with the pulley 7 and operating over 45 the pulleys 7 and 9, and driven from the former, there is belt 10.

Mounted on the framework, and rotatable in the bearings 11, 11, there is a shaft 12 and fixed on said shaft, between said bearings, there is a drive pulley 13, adapted to 55 receive a belt 13' by means of which said pulley and the shaft 12 may be driven.

Fixed on one end of the shaft 12 and aligned with the belt 10 there is an abrading wheel 14 having a peripheral groove 15, 60 lined with suitable abrading material.

This wheel 14 is surrounded by a hood 16 whose mouth 17 faces toward the belt 10 and opposite said mouth the hood has a conveyor chute 18 to be operatively connected with a suitable suction device, or fan, 65 not shown.

Fastened to the feed lever 8, opposite the wheel 14, and extending at right angles to said lever, there is a flange 19 over which the 70 belt 10 rides and the opposite side of the belt runs over an idler roller 20 adjustably mounted on the lever 8 and designed to hold said belt taut.

In front of the shaft 12, and rotatably 75 mounted in the bearings 21, 21 on the framework, there is a shaft 22, fixed to one end of which there is an upstanding arm 23. Rotatably mounted in the upper end of the arm 23 there is a spindle 24 having a free 80 end which extends across in front of the abrading wheel 14.

The individual corks, as 25, to be shaped, are cylindrical in form, with an axial opening 26 therethrough.

The cork to be shaped is fitted onto the free end of the spindle 24, said spindle extending through the axial opening 26.

The grip 27, carried by the upper end of the lever 8, may then be grasped and the 90 lever 8 moved rearwardly carrying the belt 10 into contact with the cork 25 and forcing said cork into the groove 15 of the abrading wheel 14.

The cork will be held firmly against 95 the abrading material in the groove 15 by reason of the fact that the flange 19 backs the belt 10 opposite its point of contact with said cork. The belt 10 and abrading wheel 14 travel in the respective directions indicated by the arrows in Figure 1 and the cork 100 will be gradually ground down to spherical

form, forming the completed float 27, shown in Figure 5. The groove 15, of course may be of any other contour than that of a semi-circular cross sectional form, as shown, and the finished float will have a corresponding form.

When the grip 27 is released the arm 23 will be retracted to carry the float out of contact with the abrading wheel by means of the pull spring 30, one end of which is attached to said arm 23 and the other end of which is attached to the framework in front of said arm.

The cuttings from the work will be carried off through the chute 18.

The shaft 22 carries a fixed cross arm 31, which has the adjusting screws 32, 32, threaded through the respective ends thereof and whose lower ends are adapted to contact against the framework to limit the range of movement of the arm 23 toward and from the abrading wheel.

It is obvious that mechanical changes may be made in the construction of the machine and equivalents substituted for the parts shown without departing from the principle of the invention and I hereby reserve the right to make such changes and adaptations as may be found desirable, and which do not depart from the principle of the invention as comprehended within the scope of the appended claims.

What I claim is:—

1. A machine of the character described including a rotatable abrading member, a swingable spindle forming a work holder, a revolving belt mounted to oscillate and adapted to be moved into one position into contact with the work on said spindle, whereby the work is rotated and also moved into contact with said abrading member, said belt being movable into another position to release said work.

2. A machine of the character described including a rotatable abrading member, a swingable spindle forming a work holder, an oscillatable revolving belt adapted to be moved into one position into contact with the work on said spindle, whereby the work is rotated and also moved into contact with said abrading member, said belt being movable into another position to release said work, and a yieldable member normally acting to hold the work out of contact with said abrading member.

3. A machine of the character described including a framework, a rotatable abrading member thereon, a work holder including a spindle movable into and out of operative relation with said abrading member, said spindle being provided to support the work to be operated on by said abrading member, a feed lever pivotally mounted on the framework and adapted to be oscillated toward and from the abrading member, a revolving

belt mounted on said lever, said lever being movable into one position to carry said belt into operative relation with the work on said spindle whereby said work may be moved into operative relation with the abrading member and simultaneously rotated.

4. A machine of the character described including a framework, a rotatable abrading member thereon, a work holder including a spindle movable into and out of operative relation with said abrading member, said spindle being provided to support the work to be operated on by said abrading member, a feed lever pivotally mounted on the framework, a revolving belt mounted on said lever, said lever being movable into one position to carry said belt into operative relation with the work on said spindle whereby said work may be moved into operative relation with the abrading member and simultaneously rotated by the frictional contact of the belt therewith, and a yieldable member normally holding the spindle, and the work thereon, out of operative relation with said abrading member.

5. A machine of the character described including a framework, a rotatable abrading wheel thereon, a pivotally mounted arm forming a spindle holder, a spindle on said arm adapted to receive the work, said arm being movable into operative relation with said wheel, means normally holding said spindle out of such operative relation, a pivotally mounted feed lever, a revolving belt thereon means for regulating the tension on said belt, said lever being movable into one position to carry said belt into frictional operative relation with the work on said spindle, whereby said work is rotated and simultaneously moved into operative relation with the abrading wheel.

6. A machine of the character described including a framework, a rotatable abrading wheel thereon, a work holder mounted on the framework and movable into and out of operative relation with said wheel, means for rotatably supporting the work on said holder, means for rotating the work on the said holder by frictional contact therewith and for simultaneously moving said work into operative relation with said abrading wheel, said work rotating and moving means comprising a revolving belt and a pivotally mounted support on which the belt is mounted.

7. A shaping machine including a supporting framework, a driving shaft rotatable therein, a feed lever one end of which has a bearing on said shaft, a pulley fixed on the shaft adjacent said lever, a pulley, a rotatable pulley mounted on said lever, a driving belt operable over said pulleys, a tension roller adjustable on said lever and operable against said belt, an abrading wheel aligned with said belt and having a peripheral

groove, means for driving said abrading wheel, a swingable spindle mounted on the framework and disposed opposite said abrading wheel said spindle being adapted to receive and support the work and means for manually oscillating said lever and the belt thereon, into and out of contact with the work, whereby the work may be moved into contact with the abrading wheel and simultaneously rotated by the belt released from 10 said wheel.

In testimony whereof I have signed my name to this specification.

ROBERT H. JENSON.
